UNITED STATES PATENT OFFICE.

ALFRED F. C. LOTZ, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

RHEOSTAT.

Application filed March 26, 1925. Serial No. 18,522.

My invention relates to rheostats or resistance adjusting devices, and is of particular utility in the radio field for permitting fine and accurate resistance adjustment to be readily made.

The object of the invention is to produce a simple and efficient structure by means of which a resistance wire or element of considerable length may be quickly, easily and accurately included to greater or less extent in the circuit to be controlled. On the accompanying drawings my improved apparatus is shown, and on the drawings,

Fig. 1 is a side elevational view with the housing frame in section;

Fig. 2 is a sectional view on the plane 2—2 of Fig. 1;

Fig. 3 is an end elevational view;

Fig. 4 is a sectional view on plane 4—4 of Fig. 2;

Fig. 5 is a sectional view on plane 5—5 of Fig. 4;

Fig. 6 is a sectional view on plane 6—6 of Fig. 4;

Fig. 7 is a sectional view on plane 7—7 of Fig. 1;

Fig. 8 is a sectional view on plane 8—8 of Fig. 4; and

Fig. 9 is a sectional view on plane 9—9 of Fig. 1.

The apparatus is enclosed within an oblong housing having the side wall 10 and the ends walls 11 and 12, the wall 12 being shown in the form of a detachable cover. The ends of the housing are semi-cylindrical, and in these ends are arranged the drum structures A and B. The drum structure A comprises the end wall 13 of insulating material having the central hub 14 and the cylindrical or circumferential part 15. A spider frame 16 seats in the end of the flange opposite the wall 13.

A bushing 17 extends through the hub 14 and receives the shaft 18. A sleeve 19 receives the bushing 17 and is secured in and extends from the hub 14 and just outside of the frame 16 this sleeve carries the gear pinion 20. The drum structure A is thus mounted to rotate on the shaft 18. The shaft outside of the pinion 20 has the reduced end 21 extending through the supporting plate 22 and the end is threaded to receive the nut 23 so that the shaft may be rigidly secured to the frame 22 to extend perpendicularly therefrom.

The drum structure B comprises circular end frames 24 and 25 secured on the hub sleeve 26 which holds the bushing 27 through which the drum supporting shaft 28 extends. Outside of the end wall 24 the hub sleeve 26 carries the gear pinion 29, and outside of this pinion the shaft has the reduced end 30 extending through the supporting plate 22 and engaged by the nut 31. The shaft 28 thus extends perpendicularly from the plate 22 and parallel with the shaft 18 of the drum A. The plate 22 may be supported from the inner wall 11 of the housing. As shown, the shaft ends 21 and 30 extend through the housing wall to be engaged by nuts 33.

Intermediate its ends the supporting plate 22 is clamped between the end flange 33 of the supporting bushing 34 and the nut 35 threading on said bushing. This bushing 34 extends through a supporting panel 36 and clamps in place by lock nuts 37. Through the bushing 34 extends the main or controlling shafts 38, having at its outer end the knurled knob 39. Between the supporting plate 22 and the drum structure, the shaft has secured thereto the gear 40 which meshes with the pinions 20 and 29 of the respective drum structures, so that when the knob 39 is turned, the drum structures will

be rotated, and in the arrangement shown, the gear ratio is as 3 to 1, the drums performing three revolutions for each revolution of the gear 40 or the main shaft 38. The shafts 18 and 28 may be supported at 90 their outer ends by the cover structure 12 of the housing. As shown, the end of the shaft 18 extends through a spacer block 41, and a bushing 42 extending through the wall 12, a nut 43 engaging the threaded end of the shaft so that the wall 12 may be securely clamped between the block 41 and bushing 42 and the shaft end thus supported. Likewise, the outer end of the shaft 28 extends through the spacer block 44 and the bushing 45, which are caused to clamp the housing wall 12 when the nut 46 is applied to the shaft end. A bearing block 47 may also be provided on the housing wall 12 to receive and support the outer end of the controller 105 shaft 38.

On the cylindrical surface of the drum structure A are wound two parallel lengths 48 and 48' of resistance wire, and to accurately arrange these wires on the drum, the

cylindrical side is provided with double threading 49. This drum structure is of insulating material, as has been explained, so that the wire lengths will be insulated from each other. The cylindrical wall 50 of the drum structure B is of electric conductive material, such as brass or copper, and to this drum the ends of the resistance lengths 48 and 48' are anchored in any suitable way. 10 As shown, a single piece of resistance wire may be bent intermediate its ends to form the resistance lengths or legs 48 and 48', and at its bend the wire is hooked around the anchor post 51, as shown in Fig. 1. To accommodate the resistance legs and properly space them, the wall 50 has external double threading 52 corresponding with the threading 49 on the drum structure A. 15

The resistance conductor lengths are thus anchored at one end to a metallic drum surface and are connected together electrically. At their other ends, the resistance lengths extend through passageways 53 and 54 in the drum structure A and connect with the terminals 55 and 56 extending into the interior of the drum structure from the commutator or contact rings 57 and 58 secured in the outer wall 13 of the drum structure A. These contact rings are engaged by the ends 20 of the brushes 59 and 60 extending from the terminal screws 61 and 62 secured to the housing wall 12 by nuts 63 and insulated from the wall by insulating members 64. When the brushes are in engagement with the 25 commutator rings, the circuit connected with the terminals 61 and 62 will include serially the resistance legs 48 and 48', the effective resistance length at any time being that between the connections of the legs 30 with the rings and their engagement point with the cylinder structure B. Referring to Fig. 1, the entire resistance of the legs will be inserted, as the legs are insulated from each other up to their very ends at the anchor post 51. If now the knob 39 is turned 35 in clockwise direction (from the left of Fig. 1), the drum structures will be rotated in counterclockwise direction and the resistance legs will be wound from the insulating drum structure A to the metallic drum structure B, the resistance legs being connected together electrically as they first engage with the drum structure B. When the legs have both been wound onto the drum 40 structure B, they will offer practically no resistance to the circuits including them. The gear ratio between the knob shaft and the drum shaft being as 3 to 1, the drum structures will be comparatively rapidly rotated 45 upon turning of the knob and the entire resistance range afforded by the resistance legs can be quickly run over. The resistance increase or decrease is always regular, and as the resistance element cannot wear or be 50 worn down, on account of the frictionless

winding engagement of the element with the drums, the resistance condition of the element will remain constant. Very fine, accurate and dependable resistance adjustment can therefore be quickly and readily made 55 with my device.

It may be desirable to keep the controlled circuit open and to close it only when operation is desired and it is desired to reduce resistance. Accordingly, I have provided 60 an abutment block 65 which receives the threaded section 66 of the knob shaft 38, the threading on this shaft section being double and corresponding with that on the drum structures. The block 65 is held from 65 turning by its engagement with the drum structures, and at its outer end the block has the cross arm 67 for engaging with the commutator brushes 59 and 60. When the knob shaft has been turned to place the drums 70 with the entire resistance effective, the block 65 will have been shifted along the shaft section 66 to bring its arm 67 against the brushes and then a slight further turn will release the brushes from the commutator 75 ring, so as to open the circuit. When the knob is now turned in clockwise direction, the first movement of its shaft will cause withdrawal of the block from the brushes and the brushes will engage with the commutator segments to close the circuit. Further movement then of the knob and drums will include more or less of the resistance 80 legs in circuit. As the drums are revolved to adjust for the desired resistance, the block 85 90 travels back and forth along the shaft section 66, it being remembered that this shaft turns only one revolution for three revolutions of the drum shaft, so that the threaded section 66 of the shaft may be comparatively short. 95

I do not desire to be limited to precisely what I have shown and described, as changes and modifications are possible which will still come within the scope of the invention. 100

I claim as follows:—

1. In a device of the class described, the combination of an insulating cylinder, a unitary conducting cylinder of substantially 115 the same length as said insulating cylinder, a pair of parallel resistance conductors, wound upon said cylinders, each of said cylinders being adapted for receiving substantially the entire windable portions of 120 said conductors and said conducting cylinder providing a single variable connection between the conductors, circuit connections for the conductors, and means for turning the cylinders to transfer the conductors 125 from one cylinder to the other.

2. In a device of the class described, the combination of a rotatable cylinder, a conductor adapted for winding thereon, a contact on the cylinder and in electrical con- 130

nection with said conductor, a contact arm engageable with said contact, means for winding the conductor upon and unwinding it from said cylinder, and means operable by said last means for disengaging said contact arm from said contact.

3. In a device of the class described, the combination of an insulating cylinder, a conducting cylinder, resistance conductor means carried by said cylinders, separable contacts for said conductor means, means for turning said cylinders to transfer said conductor means from one cylinder to the other, and means operable by said turning means for separating said contacts.

4. In a device of the class described, the combination of an insulating cylinder, a conducting cylinder, conductor means carried by said cylinders and adapted to have its effective length varied by said conducting cylinder, means for turning said cylinders to transfer said conductor from one cylinder to the other, a circuit connection for said conductor, and means operative at the greatest effective length of said conductor for disconnecting said circuit connection.

5. In a device of the class described, the combination of a conducting cylinder, an insulating cylinder, conductor means carried by said cylinders and adapted to be wound from one cylinder to the other, a driving

shaft extending between and connected to turn said cylinders, a circuit connection for said conductor means, and a member guided by said cylinders and operable along said shaft for controlling said connection.

6. In a device of the class described, the combination of a conducting cylinder, an insulating cylinder, conductor means carried by said cylinders and adapted to be wound from one cylinder to the other, a driving shaft extending between and connected to turn said cylinders, circuit connections for said conductor means including a pair of contact arms, one on each side of said shaft and cooperating contacts, and means operable along said shaft for disengaging said contact arms from their cooperating contacts.

7. In a device of the class described, the combination of a conducting cylinder, an insulating cylinder, conductor means carried by said cylinders and adapted to be wound from one cylinder to the other, a driving shaft extending between and connected to turn said cylinders, a circuit connection for said conductor means, and a member operable along said shaft for controlling said connection.

In witness whereof, I hereunto subscribe my name this 23rd day of March, 1925.

ALFRED F. C. LOTZ.
